PORTABLE ELECTRIC FOOD MIXER

Frederick G. J. Grise, New Braintree, Mass., and Walter C. Lovell, Hazardville, Conn., assignors, by mesne assignments, to Electric Spoon, Inc., West Brookfield, Mass., a corporation of Massachusetts

Filed June 28, 1961, Ser. No. 65,767

Term of patent 14 years

(Cl. D44—1)

FIG. 1 is a top perspective view of a portable electric food mixer, showing our new design,

FIG. 2 is a bottom perspective view thereof,

FIG. 3 is a perspective view of the upper or bail end of the mixer's motor-containing handle, and

FIG. 4 is a fragmentary sectional view, substantially on the line 4—4 of FIG. 2.

We claim:

The ornamental design for a portable electric food mixer, as shown.
